(57) **CLAIM**

The ornamental design for a rifle lower receiver, as shown and described.

DESCRIPTION

FIG. 1 is a perspective view of my new design for a rifle lower receiver;

FIG. 2 is a left side view of the rifle lower receiver shown in FIG. 1;

FIG. 3 is a front view of the rifle lower receiver of FIG. 1;

FIG. 4 is a rear view of the rifle lower receiver of FIG. 1;

FIG. 5 is a right side view of the rifle lower receiver of FIG. 1;

FIG. 6 is a top plan view of the rifle lower receiver of FIG. 1; and,

FIG. 7 is a bottom plan view of the rifle lower receiver of FIG. 1.

The broken lines are shown for illustrative purposes only and form no part of the claimed design.
